The use of both the acid mercapto compounds and the xanthylum dyes has the unexpected effect of considerably increasing the sensitizing effect of the xanthylum dyes, so that the mixture of compounds according to the invention is eminently suitable for sensitizing silver halide emulsions in the green region of the spectrum. An increase of up to as much as 40 times the sensitivity which is obtained with xanthylum dyes alone can quite easily be realised. The sensitization maxima lie between 520 and 620 nm., according to the xanthylum dyes used.

The usual silver halide emulsions may be spectrally sensitized by means of the mixtures according to the invention. The silver halide contained in these emulsions is generally silver chloride, silver bromide or a mixture of these, if desired with a small silver iodide content of up to 10 mols percent.

The binder used for the photographic layers is preferably gelatin although it may be partly or completely replaced by other natural or synthetic binders. Suitable natural binders are e.g. alginic acid and its derivatives such as salts, esters or amides, cellulose derivatives such as carboxymethylcellulose, alkyl cellulose such as hydroxyethyl cellulose, starch or derivatives thereof such as ethers or esters or carrageenates. Examples of synthetic binders are polyvinyl alcohol, partly saponified polyvinyl acetate and polyvinyl pyrrolidone.

The sensitizing mixture of xanthylum dye and acid mercapto compound may be added to the emulsions at any stage of their production, e.g. during precipitation of the silver halide, before or after the chemical ripening and preferably before casting. The conventional methods used for this are well known in the art. Both the xanthylum dyes and the mercapto compounds are added to the emulsions in the form of solutions. The solvent must, of course, be compatible with gelatin and must not have any adverse influence on the photographic properties of the emulsion. Water and alcohol are particularly suitable for use as solvents. The quantity of sensitizing xanthylum dye added may vary within wide limits, e.g. between 2 and 100 mg. preferably between 5 and 50 mg./kg. of silver halide emulsion. The quantity of acid mercapto compound added may also vary within wide limits, e.g. between 10 and 2000 mg. and preferably between 50 and 500 mg./kg. of silver halide emulsion. Particularly good results are achieved when the quantity of acid mercapto compound is a multiple of the quantity of xanthylum dye, e.g. 2 to 50 times the quantity of dye. The advantageous effect of the acid mercapto compounds is all the more astonishing in view of the high concentrations used since it is generally known that mercapto compounds act as stabilizers and when used in high concentrations severely impair the general sensitivity of silver halide emulsions. The two components of the sensitizing mixtures according to the invention may be added to the emulsions successively from separate solutions or they may be added simultaneously from a common solution.

The emulsions may also be chemically sensitized, e.g. by adding compounds which contain sulfur at the stage of chemical ripening, for example allylisothiocyanate, allylthiourea, or sodium thiosulfate. Reducing agents, e.g. the tin compounds described in Belgian patent specification Nos. 493,464 and 568,687 polyamines such as diethylene triamine or aminomethanesulfonic acid derivatives, e.g. according to Belgian patent specification No. 547,323, may also be used as chemical sensitizers.

Noble metals and compounds of noble metals such as gold, platinum, palladium, iridium, ruthenium or rhodium are also suitable as chemical sensitizers. This method of chemical sensitization has been described in the article by R. Koslowsky, Z. Wiss. Phot. 46, 65-72 (1951).

The emulsions may also be sensitized with polyalkylene oxide derivatives, e.g. with polyethylene oxide having a molecular weight of between 1,000 and 20,000, or with condensation products of alkylene oxides and aliphatic

alcohols, glycols, cyclic dehydration products of hexitols or with alkyl substituted phenols, aliphatic carboxylic acids, aliphatic amines, aliphatic diamines and amides. The condensation products have a molecular weight of at least 700 and preferably more than 1,000. These sensitizers may, of course, be combined for achieving special effects, as described in Belgian patent specification No. 537,278 and in British patent specification No. 727,982.

The emulsions may contain the usual stabilizers, e.g. homopolar or salt-type compounds of mercury which have aromatic or heterocyclic rings such as mercaptotriazoles, simple mercury salts, sulphonium mercury double salts and other mercury compounds. Azaindenes, especially tetra- or penta-azaindenes and especially those which are substituted with hydroxyl or amino groups are also suitable for use as stabilizers. Compounds of this type have been described in the article by Birr. Z. Wiss. Phot. 47, 2-58 (1952). Other suitable stabilizers include heterocyclic mercapto compounds, e.g. phenylmercaptotetraazole, quaternary benzothiazole derivatives, or benzotriazole.

A special advantage of the photographic material which has been sensitized according to the invention consists in its insensitivity to the usual additives such as color forming couplers or dyes which can be bleached.

The emulsions may be hardened in the usual manner, for example with formaldehyde or halosubstituted aldehydes which contain a carboxyl group, e.g. mucobromic acid, diketones, methanesulfonic acid esters or dialdehydes.

EXAMPLE 1

A silver chloride emulsion (prepared according to Baker, Photogr. Em. Tech. American Photogr. Publishing Co., Boston, Mass., 1948, page 217) is cast on a layer support and exposed when dry behind a yellow filter GG 435 (made by the firm of Schott) (thickness of glass 3 mm. absorption edge 435 nm.) and a grey wedge with $\frac{3}{2}$ steps and is then processed in the usual manner.

Using 6 mg. of Pyronin B (Schultz, No. 855) per kg. 40 of emulsion, a small increase in sensitivity in the green region of the spectrum (sensitization maximum 575 nm.) by two steps is achieved.

The sensitivity is considerably increased by the addition of 2 - mercaptonaphtho-[1,8-de]-oxazine-8-sulfonic acid sodium (I), 2-mercaptop-naphtho-[1,8-de]-oxazine-5-sulfonic acid sodium (II) or 2-mercaptop-naphtho-[1,8-de]-oxazine-6-sulfonic acid sodium (III) (in each case as a 0.5% aqueous solution), as can be seen from Table I.

TABLE I

	Steps $\frac{3}{2}$ behind yellow filter GG 435		After storage under tropical conditions
	Fresh	55	
Standard (no sensitizer)	5	6	
6 mg. Pyronin B	7	7	
6 mg. Pyronin B plus:			
100 mg. I	16	21	
200 mg. I	18	22.5	60
300 mg. I	18	23	
100 mg. II	16	18.5	
200 mg. II	17	20	
300 mg. II	17	20.5	
100 mg. III	16	22	
200 mg. III	18.5	23	
300 mg. III	19	23.5	

Storage under tropical conditions means that the unexposed material was stored for 4 days at 40° C. and 82% relative humidity.

The addition of the acid mercapto compound therefore results in an increase in sensitivity by up to 12 steps (this corresponds to 16 times the sensitivity) compared with an emulsion which has only been sensitized with Pyronin B, and in the case of storage under tropical conditions there is an increase by 16 steps (corresponding to 40 times the sensitivity).

EXAMPLE 2

30 mg. of Rhodamine B (Schultz, No. 864) shows, in 1 kg. of a silver chloride emulsion, a very slight sensitization at about 577 nm. The sensitivity achieved with it and that achieved after the addition of the following mercapto compounds are shown in Table II:

2-mercaptop-5-chlorobenzoxazole-7-sulfonic acid sodium (IV),
10 2-mercaptop-naphtho-[1,2-d]-oxazole-8-sulfonic acid sodium (V),
2-mercaptop-naphtho-[1,8-de]-oxazine-8-sulfonic acid sodium (I),
15 2-mercaptop-4-phenyl-thiadiazolinethione-(5) (A),
1-phenyl-5-mercaptop-tetrazole (B),
2-mercaptopbenzothiazole (C).

The non-acid mercapto compounds A, B and C used as stabilizers are used here for comparison.

TABLE II

	30 mg. Rhodamine B	Steps $\frac{3}{2}$ behind yellow filter GG 435 Schott	
		Fresh	After storage under tropical conditions
25	Alone	6	7.5
	+200 mg. IV	10.5	18.5
	+200 mg. V	19	20.5
30	+200 mg. I	19	20
	+60 mg. A	8	9
	+45 mg. B	7	11
	+30 mg. C	8	11

EXAMPLE 3

35 The following results are obtained under the same conditions with 30 mg. of Rhodanin 6 G DN (Schultz No. 866) with a sensitization maximum at 550 nm.:

TABLE III

	30 mg. of Rhodanin 6 G DN	$\frac{3}{2}$ steps behind yellow filter	
		Fresh	After storage under tropical conditions
45	Alone	1	3
	+200 mg. IV	14.5	13.5
	+200 mg. V	17	17.5
	+200 mg. I	18	19.5

EXAMPLE 4

20 mg. of a dye of the formula

(prepared, like Rhodamine B, with hexahydrophthalic acid) produces a slight sensitization in the green region of the spectrum with a maximum at 573 nm. on a silver chlorobromide emulsion described in Eder (Rezept, Tabellen und Arbeitsvorschriften," editions 20-22, W. Knapp, Halle/Saale, 1948, page 188) and on exposure behind the above mentioned yellow filter and a grey step wedge having the constant 0.1 ($\frac{3}{2}$) this sensitization provides a sensitivity of only one step. If 180 mg. of mercapto compound IV are added to the same mixture, 11 steps are obtained, in other words 10 times the spectral sensitivity.

7
EXAMPLE 5

An "ammonia" emulsion which consists of 98% of AgBr and 2% of AgI and contains 19.3 g. of Ag per kg. of emulsion is used and 10 mg. of Pyronin B produce a sensitivity of 11 steps behind a yellow filter L 489 (Agfa-Gevaert) (absorption edge 489 nm.) and a step wedge of the factor $\sqrt{2}$. If 60 mg. of mercapto Compound IV are also added, the sensitivity rises to 16 steps, in other words to 5.6 times the original value.

This sensitivity increase is also achieved by the addition of 120 mg. of mercapto Compound I.

EXAMPLE 6

In 1 kg. of the silver chloride emulsion mentioned in Example 1 10 mg. of the Pyronin dye having the constitution shown in the following formula

provide a sensitization maximum at 537 nm. The intensity is increased by the addition of mercapto compound IV.

TABLE IV

Steps $\sqrt{2}$ behind yellow filter

Dye alone	2
Dye + 10 mg. IV	4
Dye + 30 mg. IV	6
Dye + 90 mg. IV	8.5
Dye + 270 mg. IV	12

EXAMPLE 7

30 mg. of the Pyronin dye

results in a sensitization maximum at 566 nm. The sensitivities achieved in the presence of 10 g. of the color-

forming coupler 1-(4'-phenoxy-3'-sulfophenyl)-3'-hepto-decylpyrazolone-(5) are as follows:

TABLE V

Steps $\sqrt{2}$ behind yellow filter

Dye alone	8.5
Dye + 120 mg. I	16.5
Dye + 120 mg. IV	17

EXAMPLE 8

When 30 mg. of the following dye

are used under the same conditions as in the previous example, the following values are obtained:

TABLE VI

Steps $\sqrt{2}$ behind yellow filter

Dye alone	5
Dye + 120 mg. I	15
Dye + 120 mg. VI	16.5

EXAMPLE 9

6 mg. of Pyronin B are introduced into a silver chloride emulsion as in Example 1 and cast on an acetyl cellulose support. The sensitivity behind of the yellow filter described above is two steps $\sqrt{2}$. If in addition 100 mg. of 2-mercaptop-4-(p-carboxyphenyl)-thiadiazolinethione-(5) (VII) are added, this sensitivity increases to 13 steps $\sqrt{2}$, in other words to more than 10 times the original value.

EXAMPLE 10

To 1 kg. of an ammonia emulsion (see Example 5) are added: (a) the following dyes, (b) the following dyes and in addition 200 mg. of I. The sensitivity achieved is shown in Table VII.

TABLE VII

Dyes	Steps $\sqrt{2}$ behind sensitization	
	Yellow filter	Maximum
30 mg,		
	(a) 4 (b) 14	583
30 mg,		
	(a) 7 (b) 14	576
30 mg,		
	(a) 6 (b) 14	586

TABLE VII—Continued

Dyes		ClO ₄ [⊖]	Steps $\sqrt[3]{2}$ behind sensitization	
			Yellow filter	Maximum
30 mg, (H ₃ C ₂) ₂ N—		ClO ₄ [⊖]	(a) 5 (b) 13	610
30 mg, 		ClO ₄ [⊖]	(a) 11 (b) 13	587
30 mg, (C ₂ H ₅) ₂ N—		ClO ₄ [⊖]	(a) 5 (b) 10	605
30 mg, 		ClO ₄ [⊖]	(a) 10 (b) 12	545
10 mg, 		ClO ₄ [⊖]	(a) 10 (b) 13	565
10 mg, 		ClO ₄ [⊖]	(a) 8 (b) 9	566

EXAMPLE 11

6 mg. of Pyronin B in methanolic solution (1:2000) are added to 1 kg. of an ammonia emulsion as described in Example 5. The following sensitivities are obtained behind yellow filter L 489:

Dye alone	Steps $\sqrt[3]{2}$
Dye + 200 mg. VIII	10
Dye + 200 mg. XIX	12
Dye + 200 mg. X	12
Dye + 200 mg. XI	13
Dye + 200 mg. XII	13.5
Dye + 200 mg. XIII	15
Dye + 200 mg. XIV	14.5
Dye + 200 mg. XIV	15

What is claimed is:

1. A photographic material which comprises at least one silver halide emulsion layer that contains both (1) a xanthium dye of the formula:

50 in which

X is an oxygen, sulphur or selenium atom, R is a hydrogen atom or is an alkyl, aralkyl, cycloalkyl or aryl group,

R₁ and R₂, which may be the same or different are an amino group, the nitrogen atom of which may be mono- or di-substituted with alkyl groups containing up to 6 carbon atoms, cycloalkyl, aralkyl or aryl groups; or the nitrogen atom of the amino group may form a 5, 6 or 7 membered heterocyclic ring,

R₃ and R₄, which may be the same or different are a hydrogen atom, an alkyl group or an alkoxy group containing up to 6 carbon atoms,

A[⊖] is an anion

65 and (2) an acid mercapto compound of the formula
acid—Z—SH

in which

70 Z is phenylene or a heterocyclic ring selected from the group consisting of benzoxazole, naphthoxazole, benzothiazole, naphthothiazole, benzoselenazole, naphthoselenazole, benzimidazole, naphthoimidazole, oxadiazole, thiadiazole, thiadiazolinethione, selenadiazole, triazole, naphthooxazine, naphthothiazine and pyrimidine, and

11

acid is an acid group selected from the group consisting of $-\text{SO}_3\text{H}$, $-\text{SO}_4\text{H}$, $-\text{COOH}$, $-\text{PO}_3\text{H}_2$, $-\text{NHSO}_2-\text{R}_5$

and $-\text{SO}_2\text{NH}-\text{R}_5$ where R_5 is an alkyl or aryl group, or a salt anion derived from a metal salt or salt of organic nitrogen base; the acid group is attached to Z directly or via one or more vinylene groups.

2. A material as claimed in claim 1 which comprises in the silver halide emulsion layer 2 to 100 mg. of xanthylum dye per kilogram of emulsion.

3. A material as claimed in claim 2 which comprises 5 to 50 mg./kg. of xanthylum dye.

4. A material as claimed in claim 1 which comprises 10 to 2,000 mg. of acid mercapto compound per kg. of emulsion.

12

5. A material as claimed in claim 4 which comprises 50 to 500 mg./kg. of acid mercapto compound.

6. A material as claimed in claim 1 in which 2 to 50 times the weight of xanthylum dye of the acid mercapto compound is used.
